UNITED STATES PATENT OFFICE.

HARRY HARRIS, OF RICHMOND, VIRGINIA.

SHOE-REPAIR STAND.

Application filed September 12, 1925. Serial No. 56,042.

This invention relates to shoe repair stands and has for its object the provision of simple means whereby a shoe will be firmly supported in proper position to permit heels to be repaired and the operator will be relieved of the necessity of manually holding the shoe upon the support. A further object of the invention is to provide means whereby the shoe-holding elements may be easily adjusted to the size of the shoe and will be firmly retained in the adjusted position, and a still further object of the invention is to provide a repair stand of such construction that the last may be held rigidly in place without the use of extraneous fastening devices and various sizes and shapes of lasts may be interchangeably employed without requiring a rearrangement or dismantling of the parts of the stand. These several objects, and other objects which will incidentally appear in the course of the following description, are attained in the use of such an apparatus as is illustrated in the accompanying drawings, and the invention resides in certain novel features which will be particularly pointed out in the appended claims.

In the drawings:

Figure 1 is a front elevation of a repair stand embodying my invention;

Fig. 2 is a side elevation of the same partly broken away;

Fig. 3 is an enlarged detail section substantially on the line 3—3 of Fig. 2;

Fig. 4 is a detail horizontal section substantially on the line 4—4 of Fig. 3;

Fig. 5 is a detail perspective view of the shank of a last or shoe-supporting horn, and

Fig. 6 is a detail perspective view of the upper end of the standard with which the last or shoe horn is engaged.

In carrying out my invention, I employ a standard or post 1 which is preferably an integral casting and is provided with a laterally enlarged base 2 through which cap screws or the like 3 may be inserted into the floor of the workroom to rigidly secure the stand in an upright position. The standard is provided in its lower portion with a vertical slot or opening 4, and upon one wall of the slot adjacent the lower end thereof is a stop lug 5. A treadle 6 is pivoted at its rear end upon a short post 7 rising from the base 2 and extends through the slot or opening 4 to be engaged at times

under the stop lug 5, as will be understood upon reference to Figs. 1 and 2.

The upper extremity of the standard 1 is flatsided and is preferably rectangular in horizontal outline, as shown at 8, and a horizontal shoulder 9 is formed upon each side of the standard to furnish a firm support for the horizontal member 10 of bracket 11, said member 10 being constructed with a slot 12 adapted to closely engage the sides of the upper extremity of the standard, as shown in Figs. 4 and 6. The member 10 of this bracket is fitted over the upper extremity of the standard to rest upon the shoulders 9 and then keeper plates 13 are secured to the sides of the standard immediately above the bracket member so that the bracket will be firmly retained on the standard but may be adjusted across the same by manipulation of a set screw 14 mounted in the end of the bracket and bearing against the front face of the standard, as will be understood upon reference to the drawings. The sides of the standard are also cut away at the upper extremity of the same, providing recesses 15, and a socket 16 is also formed in the upper extremity of the standard communicating with the said recesses, the front and rear walls of the said socket being extended above the sides of the same to form lugs 17, as shown. The last or shoe-supporting horn 18 will be of the proper shape and size to fit within a shoe, indicated at 19, and support the same in position to be repaired, and a number of the lasts will be provided so that they may be interchangeably employed and a single stand thereby utilized in repairing shoes of a wide range of sizes and shapes. Each last is constructed with a shank 20, the lower end of which is reduced and defines a rectangular tongue or stud 21 which is adapted to fit closely within the socket 16 and between the lugs 17. Immediately above the said tongues are lateral shoulders 22 which are adapted to rest upon the upper edges of the sides of the standard which form the bases of the recesses 15 between the lugs 17. Above the said lateral shoulders 22 are other shoulders or projections 23 extending in angular relation to the said shoulders 22 whereby they may project over and rest upon the upper ends of the lugs 17. It will thus be seen that the last is supported upon the upper end of the standard so that it cannot rotate thereon and it is not necessary to employ any screws,

bolts or other extraneous fastening devices to retain the last in place. When a shoe is placed upon the last and pressure is applied thereto in repairing the shoe, the upward movement of the last from the standard is positively prevented.

To retain the shoe upon the last after it has been placed thereon by manual manipulation in the usual manner, a strap 24 is provided which spans the shoe and passes downwardly at opposite sides of the last and the standard to be connected with contractile coiled springs 25 which have their lower ends connected to the treadle 6, as shown in Figs. 1 and 2. The bight or bridging portion of the strap 24 is slit, as shown at 26, whereby it may be spread so as to pass over the breast and the back of the heel, as shown in Figs. 1 and 2, the central portion of the strap being thus formed into a pair of loops 27 which are adapted to engage the inverted heel over the largest portion thereof and thereby firmly hold the heel to the shoe and the shoe to the last. In repairing shoes with the stands now most commonly used, it is necessary for the workman to use one hand to hold the shoe against slipping along the last in order to prevent the heel of the shoe riding off the end of the last, so that the necessary support for the heel is missing. To overcome this objection, I provide the presser arm 28 which is pivotally mounted at the upper extremity of the bracket 11 and has its inner end forked, as shown at 29, whereby it may fit closely about the shoe counter immediately adjacent the heel, as shown in Figs. 1 and 2, and thereby hold the shoe against sliding upon the last. A strap 30 is attached to the under side of the presser arm between the pivot thereof and the last and extends downwardly therefrom to be connected with the treadle 6 through contractile springs 31. If desired, coupling straps 32 may be secured to the straps 24 and 30 so as to maintain them in the proper relation and prevent the strap 24 dropping away from the strap 30 so that its engagement over the shoe would be made difficult. The outer end of the presser arm projects beyond the bracket 11, and a contractile spring 33 extends between the same and the bracket and tends constantly to move the arm out of engagement with the shoe.

When a shoe is to be repaired, it is first slipped over the sole portion of the last so as to rest thereon in the usual manner and the slotted portion of the strap defining the loops 27 is engaged over the heel, after which the arm 28 is manually swung downward so that the forked end 29 thereof will bear against the shoe counter, as shown in Fig. 1. The downward movement of the presser arm into engagement with the shoe will, of course, exert a slight pressure upon the shoe in the direction of the toe thereof

so that the heel portion of the shoe will be pressed firmly against the last and after the arm has been brought down into engagement with the shoe, the treadle 6 is forced downwardly and then given a slight lateral movement so that it will be engaged under the stop lug 5, upward movement of the treadle being thereby prevented and sufficient tension being exerted upon the straps 24 and 30 to hold the shoe firmly upon the stand, leaving both hands of the workman free to engage in the repair work. While the device is intended more particularly for use in repairing heels, it may be employed in repair work upon the soles of shoes by permitting the arm 28 to remain in its substantially upright position and engaging both of the loops 27 over the shank of the shoe in advance of the breast of the heel. The straps 24 and 30 are detachably connected with the springs 25 and 31 and with the arm 28 so that either strap may be easily disconnected and rendered inoperative if the exigencies of any particular work so demands. A convenient form of coupling 90 is a snap hook, such as shown at 34. By adjusting the bracket 11 across the standard 1, the presser arm 28 may be easily set so as to properly engage a shoe of any size, it being obvious that a relatively long shoe 95 will project a greater distance from the central vertical plane of the standard 1 than a relatively short shoe and the last 20 upon which the shoes are engaged, of course, very likewise in their dimensions. After a shoe has been repaired, the treadle 6 is disengaged from the stop lug 5 and the several springs 25, 31 and 33 then at once raise the treadle and release the tension upon the straps 24 and 30 so that the presser arm 28 and the loops 27 may be easily disengaged from the shoe and the shoe removed from the last.

Having thus described the invention, I claim:

1. In a shoe repair stand, the combination 110 of a standard provided with a flat-sided socket in its upper end, lugs rising from the end walls of said socket above the side walls of the same, a last having a flat-sided tongue at the lower end of its shank to fit 115 within the socket in the standard and provided with transverse shoulders resting upon the upper ends of the said lugs and longitudinal shoulders resting upon the upper edges of the side walls of the said socket 120 between the lugs whereby rotation of the last upon the standard will be prevented.

2. In a shoe repair stand, the combination 125 of a standard, a last engageable in the upper end of the standard to support a shoe thereover, a bracket mounted upon the upper end of the standard and projecting rearwardly therefrom, a presser arm pivotally secured between its ends upon said bracket and having its front end adapted to engage 130

- the heel portion of a shoe fitted on the last, a resilient connection between the bracket and the rear end of said presser arm tending to release the arm from the shoe, a treadle mounted at the lower end of the standard, and a connection between the treadle and the presser arm in front of the bracket whereby to hold the arm in engagement with the shoe.
- 5 3. In a shoe repair stand, the combination of a standard provided with lateral shoulders adjacent its upper end, a last engaged with and supported by the upper end of the standard, a bracket having a lower slotted
- 10 member fitted over the upper end of the standard and resting on said shoulders, keeper plates secured to the sides of the standard above the said bracket member whereby to hold the same to said shoulders, means for adjusting the bracket along the 20 shoulders, a presser arm pivotally mounted upon the bracket in position to engage the heel portion of a shoe fitted on the last, means tending to hold said arm out of engagement with the shoe, and means cooperating with the standard to hold the arm in engagement with the shoe.
- 15 In testimony whereof I affix my signature.

HARRY HARRIS. [L. s.]
